C. F. WRAY.

TURNING PLUG.

APPLICATION FILED DEC. 18, 1914.

Patented Apr. 10, 1917.

UNITED STATES PATENT OFFICE.

CHARLES F. WRAY, OF ROCHESTER, NEW YORK, ASSIGNOR TO NATIONAL BRASS MANUFACTURING COMPANY, OF ROCHESTER, NEW YORK, A CORPORATION OF NEW YORK.

TURNING PLUG.

1,222,172.

Specification of Letters Patent.

Patented Apr. 10, 1917.

Application filed December 18, 1914. Serial No. 877,845.

To all whom it may concern:

Be it known that I, CHARLES F. WRAY, of Rochester, in the county of Monroe and State of New York, have invented certain new and useful Improvements in Turning Plugs; and I do hereby declare the following to be a full, clear, and exact description of the same, reference being had to the accompanying drawings, forming a part of this specification, and to the reference-numerals marked thereon.

My invention has for its object to improve the construction of turning plugs, with particular reference to the type of device embodying generally a plug that is separable from the valve body, and readily removable. Valves of this type are employed where it is desirable to cleanse the parts frequently, requiring the removal of the plug from the valve body, and it is the purpose of the present improvement to afford an arrangement that will reduce to a minimum the difficulty encountered, or work required in removing the plug from the body. A further object of the invention is to simplify the construction and lower the manufacturing cost as much as possible. To these and other ends the invention consists in certain improvements and combinations of parts all as will be hereinafter more fully described, the novel features being pointed out in the claims at the end of the specification.

In the drawings:

Figure 1 is a sectional view showing one embodiment of the invention;

Fig. 2 is a plan view of the locking member, and

Fig. 3 is a perspective view of the same.

Similar reference characters in the several figures indicate the same parts.

In the present embodiment, the invention comprises a valve body having inlet and outlet ports A and B and a tapered bore C. The bore C terminates in upper and lower edges D and E, and is adapted to receive a plug F having an opening G, to be aligned with the ports A and B when rotated, while H is a handle carried by the plug for operating it.

At its lower end, the plug F is recessed or cut away at I, and is further provided with a reduced portion, designated at J. The reduced portion J is preferably in the form

of a piece separate from the body portion of the plug and carries a threaded post K for engagement with a correspondingly threaded opening in the plug, the post K being held in place by a friction pin L which is driven through suitably provided openings in the valve plug and in the post.

The reduced portion J carries an enlargement or head M at its lower end, affording a shoulder N on which is supported a spring O for a purpose that will presently appear. Resting upon the spring O is a follower, preferably in the form of a sleeve P which has an inwardly directed flange Q at the top. The follower P constitutes a housing for the spring O and is arranged for yieldable engagement with a locking member or plate, which I will now describe.

The valve plug is held in operative relation to the valve body by a readily removable retaining device which is located between the valve body and the reduced lower end of the valve plug by means of the spring actuated follower already described. To this end I employ a locking member or plate R having a slotted portion S which engages the plug in the manner shown in Fig. 1. The locking member is recessed on its upper surface, as shown at T for engagement with the lower edge E of the valve body, whereby the parts are held together with sufficient friction to prevent accidental displacement.

The lower surface of the locking member is engaged by the follower P, which, through the action of the spring Q, serves to retain the locking member tightly against the valve body and thus hold the plug in operative relation with the valve body. When it is desired to clean the parts, it is necessary to remove the locking member R, and in order to accomplish this quickly and with little difficulty I provide the locking member with a projecting portion or handle, preferably of the form shown, as designated at U. The shoulder formed on the locking member by means of the recessed portion T is preferably beveled, as at V, and the edge of the plate is also beveled at points adjacent to the slotted portion S, as indicated at W, in order to provide surfaces that will permit the locking member to be readily placed in, or removed from locking position.

With the parts in the position shown in

Fig. 1, in order to remove the plug from the valve body it is only necessary to impart a slight downward movement to the handle U, at the same time drawing the locking plate laterally, after which the plug can be removed from the valve body. The construction affords an extremely simple arrangement which can be manufactured at a reasonable cost and can be readily operated. The parts are so arranged that they can be quickly separated for purposes of cleaning, and the structure is entirely practical for use with liquid foods such as milk, from the standpoint of sanitary requirements.

I claim as my invention:

1. The combination with a valve body, of a rotary plug having a reduced lower end, a removable locking member slotted to engage said reduced end of the plug and adapted to be positioned against the valve body, said locking member being recessed on its upper surface to engage the valve body, a shoulder at the end of the reduced portion of the plug, a follower arranged on the plug above said shoulder and having an inwardly directed flange at its top, and a

spring positioned between said shoulder on the plug and the flange on the follower.

2. The combination with a valve body, of a rotary plug, a locking member slotted to engage the plug, said locking member being disposed between the valve body and the lower end of the plug and provided with a handle or projection whereby it can be positioned or removed, a follower arranged on the plug and engaging said locking member, and a spring coöperating with the follower.

3. The combination with a valve body, of a rotary plug, a locking member slotted to engage the plug, said locking member being disposed between the valve body and the lower end of the plug and provided with a handle or projection whereby it can be positioned or removed, a follower arranged on the plug and engaging said locking member, and a spring coöperating with the follower, the follower embodying a housing for the spring.

CHARLES F. WRAY.
